FRANK E. MARCY, OF SALT LAKE CITY, UTAH, ASSIGNOR, BY MESNE ASSIGNMENTS,
TO ALLIS-CHALMERS MANUFACTURING COMPANY, A CORPORATION OF DELA-
WARE.

AGITATOR.

1,082,431.

Specification of Letters Patent.

Patented Dec. 23, 1913.

Application filed February 27, 1909. Serial No. 480,359.

To all whom it may concern:

Be it known that I, FRANK E. MARCY, a citizen of the United States, residing at Salt Lake City, in the county of Salt Lake 5 and State of Utah, have invented a certain new and useful Improvement in Agitators, of which the following is a specification.

This invention relates to improvements in the construction of agitators and in particular to such construction as applied to agitating tanks for liquids such for instance as Pachuca tanks for the agitation of slimes.

The object of the invention is to provide a simple and efficient method of maintaining a constant circulation of liquid within a tank by the application of mechanical means.

A clear conception of the invention can be obtained by referring to the accompanying drawings in which like reference characters designate like parts in different views.

Figure 1 is a central vertical section of an agitating tank constructed according to the invention. Fig. 2 is a plan view of same.

25 The tank 1 having the conical bottom 2 is held in a vertical position by the braces 9. A pipe 3 having the flange 7 upon its lower end is held in a vertical position in the center of the tank 1 by means of radial braces.

30 4. A short pipe 8, having its axis at right angles to that of pipe 3, is attached to the flange 7, so that an opening through the wall of the pipe 8 forms a connection between the interior of the pipe 8 and that 35 of the pipe 3. The pipes 3, 8, are supported within the tank so that solution may freely enter at the ends of the horizontal pipe 8 and they are readily detachable and removable from the tank. A horizontal shaft

40 6 supported by the bearings 5 in the bottom 2 of the tank 1 passes through the pipe 8, so that its axis coincides with that of the pipe 8. The shaft 6 supports a pulley 17 on the exterior of the tank 1 and the screw 45 pumps 10, 11, on the interior of the tank 1 and the pipe 8. These screw pumps 10, 11, are located in the inlets of the pipe 8 and are right and left hand in construction. The motor 16 is connected with the pulley 17

50 through the medium of the belt 18. The discharge opening 12 in the bottom 2 of the tank 1 is located in the center of the tank 1 directly above a gate valve 13. The elbow

14 leading from the gate valve 13 may lead to any desired source. The inlet 15 is attached to a supply of compressed air or liquid not shown.

In operation of the device the solution to be agitated is admitted into the upper part of the tank. The motor 16 is set in motion, 60 causing the screw pumps 10, 11, to revolve and force the liquid up through the pipe 3. The solution may freely enter horizontal pipe 8 at its ends and the inflowing solution serves to prevent packing of any solids 65 that may be in suspension in the bottom portions of the tank. As the liquid rises in the pipe 3, it is finally discharged from the top opening of said pipe 3 and flows back toward the bottom 2 of the tank 1. If there 70 be solids in the solution and they should tend to clog the lower part of the tank 1, air or liquid under pressure can be admitted through the pipe 15. In discharging the contents of the tank 1, the gate valve 13 75 is opened and the material passes out through the elbow 14.

It should be understood that it is not desired to be limited to the exact details of construction shown and described, for obvious modifications will occur to a person skilled in the art.

It is claimed and desired to secure by Letters Patent:

1. In an agitator, the combination of a 85 tank, an upright pipe centrally therein and supported thereby, a lower pipe connected transversely to said upright pipe and having an end freely opening into said tank whereby solution may enter freely at said 90 end of said pipe, a single shaft extending into said lower pipe, pumping means on said shaft within said lower pipe, and driving means on said shaft without said tank.

2. In an agitator, the combination of a 95 tank, an inverted T-pipe in said tank, said pipe being spaced from the tank, and means in the horizontal portion of said T-pipe for pumping the tank contents through the upright portion of said T-pipe.

In testimony whereof, I affix my signature in the presence of two witnesses.

F. E. MARCY.
